RICHARD A. KEARSLEY, OF MILFORD, MASSACHUSETTS, ASSIGNEE TO DRAPER CORPORATION, OF HOPEDALE, MASSACHUSETTS, A CORPORATION OF MAINE

LET-OFF MECHANISM FOR LOOMS

Application filed August 27, 1929. Serial No. 388,701.

This invention relates to let-off mechanisms for looms and more particularly is directed to let-off mechanism of the positive type.

It is now the ordinary practice to provide looms with let-off mechanisms which may be either of the positive or friction type in order to supply the warp to the weaving instrumentalities and to control the supply in accordance with variations in tension manifest in the warp itself. It has also been proposed to positively rotate the warp beam gradually faster from full to empty beam by the use of compensating devices which may indicate the amount of warp on the beam at any time, but these prior devices have been open to the objection that the tension of the warp would vary throughout the weaving operation and this defect has been deflected in the finished cloth.

20 The recurring changes in the warp tension have frequently resulted in thin places in the cloth when the filling fails to be laid in the shed, and particularly is this the case when the loom having a positive let-off is run for several picks without laying filling. For instance, should a loom having a positive let-off be run without laying filling in the shed, the usual let-off pawl will act to let-off the warp to some extent, with the result that the warp tension will be changed and the warp slackened; thus emphasizing the width of the thin places in the cloth primarily caused by the absence of filling.

One of the objects of the present invention is to overcome the above well-known conditions and to provide means whereby more uniform and perfect cloth may be woven throughout the loom operation. In accordance with the present invention a positive let-off mechanism is provided which, while furnishing the necessary amount of warp for weaving, maintains a constant uniform and unvarying tension on the warp, regardless of the amount of warp let-off from the warp beam, and regardless of whether filling is or is not laid in the shed during one or more picks, thus eliminating the formation of thin places in the resulting cloth.

The invention and novel features therein will best be made clear from the following

description and accompanying drawings of one good practical form thereof.

In the drawings, Fig. 1 is a side elevation showing the rear portion of a loom provided with the present invention, some of the parts being broken away.

Fig. 2 is a rear elevation of the loom represented in Fig. 1;

Fig. 3 is an enlarged detail showing portions of the mechanism for controlling the positive rotative movement of the warp beam;

Fig. 4 is an enlarged detail, some of the parts being broken away and others shown in section, and representing more particularly certain detailed features of the present invention;

Fig. 5 is an enlarged sectional detail showing the warp tension equalizer and its mounting;

Fig. 6 is a rear perspective of the loom with some of the parts omitted for clearness of illustration.

The loom frame 1 may be of usual construction and is provided with bearings 2 one at each side of the loom for the support of the warp beam 3 on which the warp *a* is wound, and from which the warp is led to the weaving instrumentalities.

In accordance with the present invention the rotative movement of the warp beam for letting-off the warp is controlled by positive mechanism which may be of any desired type but is herein shown as of the general character shown and described in the Charles F. Roper Patent No. 843,181, February 5, 1907.

At one end the warp beam 3 is provided with a toothed wheel or gear 4 which meshes with a pinion 5 secured to a shaft 6 on which is loosely mounted the ratchet wheel 7 having driving connection with the shaft through a manual resetter of the general character of that disclosed in the Roper patent hereinbefore mentioned. Loosely mounted on the shaft 6, or on a support concentric therewith, is a pawl carrier 8 (Figs. 1 and 3) having a pawl 9 pivoted thereto as shown and normally under the influence of a light spring 10 to retain the pawl in operative engagement with the ratchet.

Connected to the pawl carrier 8 at 11 is an actuating rod 12 which may be appropriately reciprocated from any going part of the loom and, as shown in the present instance is given its reciprocating movements through 5 a pin 13 connected to one of the lay swords, as, for instance, by a riser 14 secured to the lay rock shaft 15. The actuator 12 is provided with a slot 16 which engages the pin 13 so that the actuator is susceptible of lost motion. The pawl carrier 8 is normally under the influence of a spring 17, one end of which is connected to the pawl carrier at 18 and the other to a fixed part of the loom as 10 at 19, the construction being such that during its idle stroke the pawl will be retracted by the light spring 17 and on its forward or active stroke will be positively actuated by the means hereinbefore described, to effect 15 20 rotative movement of the warp beam.

It is desirable that there shall be a speed reduction mechanism between the ratchet wheel 7 and the warp beam, and as this is clearly shown and described in the Roper patent hereinbefore mentioned, and may be of usual type, its description here is deemed unnecessary, since the details thereof form no part of the present invention.

Extending from the pawl carrier 8 is a 30 stop 20 which is adapted to engage a cooperating stop 21 (Fig. 3) adjustably supported on an arm 22 which may be loosely mounted on the shaft 6 or a part co-axial therewith. From the construction thus far described it 35 will be apparent that should the arm 22 be raised or lowered, it will alter the position of the stop 21, and consequently govern or control the idle or retracting stroke of the pawl carrier 8 to thereby vary the amount 40 of warp let-off from the warp beam.

Mounted at each side of the loom, and shown in the present instance above the warp beam, is a bracket or support 23, which may be adjusted in the vertical plane by means 45 of the bolts 24 which pass through slots 25.

Each of the brackets 23 carries a guide-way 26 in which is mounted a block 27 adapted for sliding movement towards and from the front of the loom, and mounted in the 50 blocks 27 at opposite sides of the loom is a warp tension equalizer 28 which may be constituted as a roll about which the warp passes from the warp beam to the weaving instrumentalities.

The warp tension equalizer is normally 55 under the influence of a weight to maintain uniform tension on the warp passing about it, and in the present instance of the invention the warp tension equalizer or the block 27 in which it is mounted is connected to a flexible member 29 shown in the present instance as a sprocket chain which passes about a guide or sprocket wheel 30 mounted on a rearwardly projecting portion 31 of the 60 bracket 23. The flexible member 29 then

passes frontwardly of the loom and over a sprocket wheel 32 mounted on a transversely extending shaft 33 which is itself carried between the two brackets 23 at opposite sides of the loom. The flexible member 29 passes 70 downwardly from the sprocket wheel 32 over a guide sprocket 34 mounted on the loom frame and at its lower end the flexible member 29 is connected to a weighted lever 35 on which is mounted a weight 36 which may be 75 adjustable longitudinally of the lever 35. The lever 35 is mounted for rocking movement on the loom frame at 37 and to the hub portion of the lever 35 the flexible member 80 is connected as at 38. If desired in some cases the hub portion of the lever 35 is provided with a projection 39 carrying a pin 40 which bears upon one side of the flexible member 29, the construction being such that the flexible member 29 is constantly under 85 the influence of the weight 36 to exert a pull upon the warp tension equalizer 28 in a direction to impart uniform tension on the warp.

The flexible member 29 may be connected 90 to the warp tension equalizer to exert its constant stress thereon under the action of the weight 36 in any suitable manner, but as herein shown the sliding block 27 is provided with a lug 41 to which the end portion of the 95 flexible member 29 may be secured by a bolt or pin 42.

In accordance with the present invention the function of the warp tension equalizer is to exert a constant and uniform tension on the warp under the stress of the weight 36 and consequently the warp coming from the warp beam is directed in runs about the warp tension equalizer. To this end the bracket 23, as indicated in Fig. 4, is provided with 100 a bearing 43 in which is supported a warp director or guide 44. The mounting for the guide 44 is contrived to direct the lower run of the warp α in parallelism with the upper run of the warp α about the warp tension 105 equalizer, the result being that the stress of the warp tension equalizer under the action of the weight 36 will normally tend to elongate the loop of the warp and the parallel runs thereof.

The warp tension equalizer is thus mounted for movement towards and from the front of the loom, or in a substantially horizontal direction and the adjustability of the bracket 23 as hereinbefore described enables the two 110 runs of the warp α to be maintained in parallelism by adjustment of the brackets in the vertical direction in accordance with the lead of the warp as it passes from the warp tension equalizer to the weaving instrumentalities.

From the construction described as an embodiment of the present invention it will be noted that the tension of the warp is always 115 dependent upon the stress of the weight 36 120

acting through the flexible member 29, and since the stress of the weight remains constant throughout the weaving operation the tension of the warp remains uniform and constant, regardless of the amount of warp 5 let-off from the warp beam by its positive rotative movement.

Mounted on the transversely extended shaft 33 at the side of the loom opposite the flexible member 29 is a sprocket wheel 45, and passing over the sprocket wheel 45 is the flexible member or sprocket chain 46 which extends downwardly and has secured to it a hook 47 the lower end of which is engaged with a pin 48 as indicated in Fig. 2, which extends from the arm 22, the construction being such that as the warp tension equalizer 28 is moved towards and from the front of the loom it will actuate the shaft 33 through the flexible member 29 and cause the flexible member or chain 46 to rise or fall in accordance with the direction of movement of the shaft 33, thereby determining the position of the arm 22 and the stop 21 connected therewith, and consequently governing the extent of the idle stroke of the pawl carrier 8; and since the amount of rotation of the warp beam by the positive let-off is governed by the extent of idle stroke of the pawl carrier, it will be noted at once that the amount of let-off is under control of the warp tension equalizer.

It is desirable that the warp tension equalizer shall remain parallel to the axis of the warp beam throughout the movements of the equalizer, and since the warp tensioning weight, in the illustrated form of the invention, is connected to one end of the equalizer by the flexible member 29, it is expedient that the flexible member 29 be formed as a sprocket chain so that it may rotate the transversely extending shaft 33; and likewise the flexible connection 46 is formed as a second sprocket chain the upper end whereof is connected to the tension equalizer or the block 27 at the side of the loom opposite the sprocket chain 29, as indicated more clearly in Figs. 2 and 6, while its lower portion is connected to the positive let-off control arm 22, as hereinbefore described. The result is that as the warp tension equalizer moves towards and from the front of the loom and thus controls the amount of let-off without variation in warp tension, it will remain parallel to the axis of the warp beam through the means described. The plane of the warp between the equalizer and front of the loom should be maintained in substantial parallelism with the lower run of the warp between the guide roll 44 and equalizer 28, and since the frontward lead of the warp from the equalizer may vary under different weaving conditions or in different looms, the brackets 23 which support the tension equalizer are adjustable 65 to bring the frontward lead of the warp into

the desired parallel relation with the lower run between the guide roll 44 and the equalizer, a condition readily accomplished by angular change in the position of the brackets 23.

The guide roll 44, as described, is mounted in the open bearings 43 formed on the brackets 23 with the result that the warp beam may be readily placed in the loom or removed therefrom by simply taking out the guide roll 44 temporarily. Thus in starting to weave with a new warp it is usually the practice to run the loom and let-off for a short time until the frontward lead of the warp plane becomes established and any broken ends pieced up, whereupon the brackets 23 carrying the guide roll may be adjusted to bring the two runs of the warp leading about the equalizer into parallel relation.

During the beat up and formation of the shed the warp is subjected to a sudden impulse or "bump" especially on the beat up, and to compensate for this effect upon the warp tension equalizer the sliding block 27 in which the warp tension equalizer is mounted, is provided with a check which, while permitting the necessary give to the warp equalizer during the shed formation and the bump of the beat up, will retard the warp tension equalizer from sudden movement towards and from the front of the loom, thus contributing to the maintenance of the uniform tension in the warp throughout the weaving operation.

As one convenient form of check for the above purpose, and as shown in Fig. 5, the block 27 has mounted thereon at 49 a check arm 50 provided with an eccentric portion 51 having teeth 52 which are engaged with the teeth 53 on a block 54, and the check arm 50 is normally under the influence of a spring 55 one end of which is connected to the check arm 50 and the other to an adjusting device or screw 56 (Fig. 5).

The under side of the block 54 is preferably provided with a friction pad 57 which bears upon the surface of the guide 26 with the result that while the friction pad 57 will permit the warp tension equalizer and its block mounting to move towards and from the front of the loom under the uniform stress of the weight 36, it will serve to check the bump during shed formation and the beat up.

It may be desirable at times to vary the action of the friction pad, that is, to make it more or less in accordance with the character of the cloth being woven, or other conditions, and to this end the block 27 has a recess 58 in which the block 54 is mounted for a limited amount of longitudinal movement, and in order to adjust the position of the block 54 for the desired conditions there is an adjusting device or screw 59 at each end of the recess 58, whereby adjustment of the block 54

lengthwise will cause the eccentric portion 51 of the check arm 50 to press with more or less energy upon the block 54 and consequently upon the pad 57 carried thereby.

5 The construction described constitutes a complete organization for maintaining uniform and equal tension on the warp throughout the weaving operation, regardless of the amount of warp let-off from the warp beam and regardless of whether filling is laid in the 10 shed or not.

15 What is claimed is:

1. In a let-off mechanism for looms, the combination of the warp beam on which the warp is wound, a positive let-off for actuating the warp beam to let-off the warp, a warp tension equalizer mounted for movement towards and from the front of the loom, means for directing the warp in parallel runs about the warp tension equalizer from full to empty warp beam that the equalizer may exert unvarying tension on the warp loop throughout the weaving operation, a weight normally active upon the warp tension equalizer in a direction to maintain uniform tension on the warp throughout the weaving operation, and means governed by movement of the equalizer toward and from the front of the loom to vary the amount of let-off from the warp beam without changing the uniform warp tension.

2. In a let-off mechanism for looms, the combination of the warp beam on which the warp is wound, a positive let-off for actuating the warp beam to let-off the warp, a warp tension equalizer mounted for rectilinear movement towards and from the front of the loom, a warp guide between the warp beam and equalizer for directing the warp in parallel runs about the equalizer from full to empty beam, a weight, a connection between the weight and warp tension equalizer for causing the weight to act upon the warp tension equalizer in a direction to elongate the parallel runs of the warp loop and maintain a uniform tension upon the warp throughout the weaving operation, a let-off controller shaft, connections between the let-off controller shaft and equalizer for causing rotation of the controller shaft by movements of the equalizer towards and from the front of the loom to regulate the operation of the positive let-off and let-off the warp through 105 rotative movement of the controller shaft.

3. In a loom, the combination of the warp beam on which the warp is wound, a positive let-off for turning the warp beam to let-off the warp, a warp tension equalizer mounted for movement towards and from the front of the loom, means for guiding the warp tension equalizer in its movements, a warp guide between the warp beam and equalizer for directing and maintaining the warp in parallel runs about the warp tension equalizer from full to empty beam, a weight, a flexible

member connected to the warp tension equalizer and to the weight, guiding means for the flexible member between the warp tension equalizer and weight to cause the flexible member to exert a pull upon the warp tension equalizer and maintain uniform tension of the warp throughout the weaving operation, and a let-off controller actuated by the flexible member to vary the positive rotative movement of the warp beam without varying the uniform tension of the warp.

4. In a let-off mechanism for looms, the combination of the warp beam on which the warp is wound, a positive let-off for turning the warp beam to let-off the warp, a warp tension equalizer mounted for movement in a substantially horizontal plane towards and from the front of the loom, means for directing the warp in parallel planes about the equalizer, a weight normally acting upon the equalizer in a direction to maintain uniform tension on the warp during weaving, means for checking too free movement of the equalizer under the stress of the warp and weight, and means governed by substantially horizontal movement of the warp tension equalizer to control the positive rotative movement of the warp beam without changing the uniform tension of the warp.

5. In a let-off mechanism for looms, the combination of the warp beam on which the warp is wound, a positive let-off for turning the warp beam to let-off the warp, a warp tension equalizer constituted as a roll extending transversely of the loom, brackets at each side of the loom provided with guideways in which the equalizer has movement towards and from the front of the loom, a warp guide mounted in said brackets between the warp beam and equalizer for directing and maintaining the warp in parallel runs about the warp tension equalizer as the diameter of the warp varies, a weight, a flexible member connecting the weight and equalizer, guides about which the flexible member passes between the weight and equalizer to cause the equalizer to pull rearwardly in the loop of the warp with a tendency to elongate the parallel runs of the loop and maintain uniform tension on the warp throughout the weaving operation, and means governed by movement of the equalizer toward and from the front of the loom for controlling the positive let-off without varying the warp tension.

6. In a let-off mechanism for looms, the combination of a warp beam on which the warp is wound, a positive let-off for rotating the warp beam to let-off the warp, a warp tension equalizer constituted as a roll extending transversely of the loom and mounted for movement towards and from the front of the loom, means for directing the warp in parallel runs about the equalizer, a weight and flexible connection between the weight

- and equalizer acting in a direction to maintain uniform tension on the warp throughout the weaving operation, and a let-off controlling shaft actuated by the flexible connection upon movement of the equalizer towards and from the front of the loom to regulate the operation of the positive let-off and let-off the warp without varying the uniform tension of the warp.
10. In a let-off mechanism for looms, the combination of a warp beam on which the warp is wound, a positive let-off for rotating the warp beam to let-off the warp, a warp tension equalizer constituted as a roll extending transversely of the loom and mounted for movement towards and from the front of the loom, a check for retarding too free movement of the equalizer towards and from the front of the loom, means for directing the warp in parallel runs about the equalizer, a weight and flexible connection between the weight and equalizer acting in a direction to maintain uniform tension on the warp throughout the weaving operation, and a let-off controlling shaft actuated by the flexible connection upon movement of the equalizer towards and from the front of the loom to regulate the operation of the positive let-off and let-off the warp without varying the uniform tension of the warp.
11. In a let-off mechanism for looms, the combination of the warp beam on which the warp is wound, a positive let-off for actuating the warp beam to let-off the warp, a warp tension equalizer mounted for movement towards and from the front of the loom, means for directing and maintaining the warp in parallel runs about the warp tension equalizer as it moves towards and from the front of the loom, a weight normally active upon the warp tension equalizer in a direction to elongate the parallel runs of the warp loop and maintain uniform tension on the warp during variations in the diameter of the warp mass on the beam and means for maintaining the warp tension equalizer in parallel relation to the axis of the warp beam as the equalizer moves towards and from the front of the loom.
12. In a let-off mechanism for looms, the combination of the warp beam, a positive let-off for rotating the warp beam to let-off the warp, a bracket at each side of the loom having a guideway, a warp tension equalizer mounted in said guideways for movement towards and from the front of the loom, means for directing the warp in parallel runs about the warp tension equalizer, a weight, a flexible connection between the weight and one end of the warp tension equalizer to maintain uniform tension on the warp, a transversely extending shaft mounted in the brackets and rotated by movement of said flexible connection, a second flexible connection between the opposite end of the equalizer and positive let-off and movable by rotation of the transversely extending shaft to maintain the equalizer in parallel relation to the warp beam and to let-off the warp responsive to movement of
13. In a let-off mechanism for looms, the combination of the warp beam on which the warp is wound, a positive let-off for actuating the warp beam to let-off the warp, a warp tension equalizer mounted for movement towards and from the front of the loom, means for directing and maintaining the warp in parallel runs about the warp tension equalizer as it moves towards and from the front of the loom, a weight normally active upon the warp tension equalizer in a direction to elongate the parallel runs of the warp loop and maintain uniform tension on the warp during variations in the diameter of the warp mass on the beam and means for maintaining the warp tension equalizer in parallel relation to the axis of the warp beam as the equalizer moves towards and from the front of the loom.
14. In a loom, the combination of the warp beam on which the warp is wound, a positive let-off for turning the warp beam to let-off the warp, a warp tension equalizer mounted for movement towards and from the front of the loom, means for guiding the warp tension equalizer in its movements, means for directing the warp in parallel runs about the warp tension equalizer, a weight, a flexible member connected to the warp tension equalizer and to the weight, guiding means for the flexible member between the warp tension equalizer and weight to cause the flexible member to exert a pull upon the warp tension equalizer and maintain uniform tension of the warp throughout the weaving operation,

the warp tension equalizer without variation in warp tension.

13. In a let-off mechanism for looms, the combination of the warp beam, a warp tension equalizer movable towards and from the front of the loom, means for directing the warp in parallel runs about the warp tension equalizer, a weight, a sprocket chain connected to the weight and to one end of the warp tension equalizer to maintain uniform tension on the warp, a transversely extending shaft having a sprocket wheel about which the sprocket chain passes and by which the shaft is rotated by movement of the sprocket chain, a second sprocket wheel rotatable by the transversely extending shaft, a second sprocket chain connected to the other end of the warp tension equalizer and passing about the second sprocket wheel to maintain the equalizer in parallel relation to the warp beam, and a positive let-off governed by the second sprocket chain to let-off the warp responsive to the equalizer movement without varying the tension on the warp.

14. In a let-off mechanism for looms, the combination of the warp beam, a bracket at each side of the loom having a guideway, a warp tension equalizer mounted in said brackets for movement towards and from the front of the loom, a weight connected to the warp tension equalizer exerting a tendency to lengthen the parallel runs of the warp loop to maintain uniform tension on the warp, means for changing the position of the brackets in accordance with the lead of the warp from the equalizer towards the front of the loom, a warp guide mounted on the bracket between the warp beam and equalizer to maintain the upper and lower runs of the warp in parallel relation as the position of the brackets is changed, a positive let-off, and means controlled by movement of the warp tension equalizer towards and from the front of the loom for governing the amount of warp let-off from the warp beam without varying the warp tension.

15. In a positive let-off mechanism for looms, the combination of the warp beam on which the warp is wound, a pivoted bracket at each side of the loom having a guideway, a warp tension equalizer constituted as a roll mounted in the guideway of the brackets for bodily movement in a rectilinear path towards and from the front of the loom, a warp guide mounted in said brackets below the path of movement of the warp tension equalizer for directing the warp in a loop about the equalizer, means for adjusting the brackets about their pivotal mountings to bring the upper run of the warp into parallelism with the lower run, a weight normally acting upon the warp tension equalizer to maintain uniform tension on the warp from

full to empty beam, a positive let-off mechanism, and means controlled by the movement of the equalizer towards and from the front of the loom in its rectilinear path for governing the amount of warp let-off from the warp beam without varying the warp tension.

In testimony whereof, I have signed my name to this specification.

RICHARD A. KEARSLEY.
